FERDINAND BURCHARTZ, OF NEW YORK, N. Y., ASSIGNOR TO BURCHARTZ FIRE-PROOFING COMPANY, INC., A CORPORATION OF NEW YORK.

HOLLOW BLOCK FOR REINFORCED-CONCRETE FLOORS.

1,219,532.

Specification of Letters Patent. Patented Mar. 20, 1917.

Application filed January 27, 1914. Serial No. 814,624.

To all whom it may concern:

Be it known that I, FERDINAND BURCHARTZ, a citizen of the United States, and resident of the borough of Manhattan, city, county, and State of New York, have invented a certain new and useful Improvement 5 in Hollow Blocks for Reinforced-Concrete Floors, of which the following is a specification.

10 My invention relates to the construction of monolithic concrete floors and has for its object to provide a hollow block adapted particularly for use in floors of this type. A further object of my improvement is to provide 15 a simple closure whereby the open ends of said blocks are closed and a complete hollow block is readily produced and which is easily placed in operative position on the blocks. Other objects of my invention will 20 appear from the description hereinafter and the features of novelty will be pointed out in the appended claims. The present application is in part a continuation of my application Serial Number 586,608 filed October 25 12, 1910.

An embodiment of my invention is illustrated in the accompanying drawings in which Figure 1 is a cross-sectional view of one form of my improved block; Fig. 2 is a 30 plan view of the closure; Fig. 3 is a perspective view of a slightly different form of block with a closure applied thereto; Fig. 4 is a plan view of the closure shown in Fig. 3; Fig. 5 is a plan view of a two-way reinforced floor with one form of my improvement included therein and Fig. 6 is a detail section thereof on the line 6-6 of Fig. 5.

In the form of my invention shown in Fig. 1 the open ended block 10 is formed 40 with flanges 11 extending along opposite lower edges and parallel with the major axis of the block, the said block having its two side walls each provided with an outwardly open recess or channel 12 extending lengthwise 45 thereof and preferably of dove-tail shape as shown. In order that the open ends of the block 10 may be effectively closed in a simple manner against the entrance of concrete or other material I provide, for instance, the U-shaped closure shown in Fig. 2 and comprising the metal or other plate 13 and the side members 14 extending at an angle thereto. The said side members 14 are adapted to be inserted into the ends of op-

posite recesses 12 so as to extend along the 55 sides of the block and serve to maintain the plate 13 in contact with and across an open end of the block, it being understood that said plate 13 is of a size to completely close the end of the axial opening of said block 60 and with no part extending either above or below the upper and lower surfaces of the block. The side members 14 also lie entirely within the recesses 12 and preferably frictionally engage the side walls of the 65 block so as to maintain the plates 13 against accidental displacement in the direction of the axis of the block, the recesses 12 preventing any substantial movement of the closures in any direction transverse to said axis. It 70 will of course be obvious that the recesses 12 need not extend throughout the entire length of the block but need only extend inwardly a sufficient distance from each end to properly receive the side members 14 in such a manner 75 that the plates 13 may be brought into contact with the ends of the block.

As shown in Fig. 4 the closure is so constructed that the distance between the ends of the side members 14^a is normally less than 80 the horizontal transverse width of the block 10^a, the resiliency of the material tending to maintain said members 14^a in and return them to this normal position. In this form the closure is applied over the ends of the 85 block 10^a by springing the members 14^a apart and then moving the same lengthwise of said block until the plates 13^a contact with an open end thereof. The resilient action of the members 14^a will firmly clamp the 90 closure in position to close the open ends of said block with no part thereof extending above or below the upper or lower surface of said block as clearly shown in Fig. 3. It is of course to be understood that the closure 95 shown in Fig. 4 may be used in connection with the block 10 of Fig. 1 and also that the closure illustrated in Fig. 2 may be utilized in connection with the block 10^a of Fig. 3 and in either case will form a complete closure 100 for the axial openings of the blocks.

In Figs. 5 and 6 I have shown a section of a floor constructed of the blocks 10^a and closures 13^a-14^a. As illustrated the blocks are set up in rows with the axes of the 105 blocks all extending in the same direction, the rows being spaced apart to form channels projecting in one direction and the ends

of the blocks being separated to form channels extending in another direction at right angles. The bottoms of the said channels are formed by means of soffit pieces 15 which are 5 located between said blocks and between the ends thereof and which also serve to maintain the said blocks in proper spaced relation in the floor, the construction of which may be accomplished with the aid of temporary scaffolding in the usual manner. The blocks 10 shown in Fig. 1 may be set up in the same way in which case the abutting flanges 11 of adjacent blocks will form means for spacing the blocks in one direction and bottoms for one set of channels, while soffit pieces 15 may be utilized to space the ends of the blocks apart and form bottoms for the other set of channels. Either type of block and closure may be incorporated 10 in a floor with the axis of adjacent blocks extending at right angles to each other for instance, as shown in my application Serial Number 586,608 hereinbefore referred to. In whatever relation the said 15 blocks are set up the channels are adapted to receive the usual tie rods 16 and are filled with concrete or other coalescent material to form intersecting beams, which material as before stated is prevented from entering the 20 blocks 10 or 10^a by the closures 13 or 13^a.

The closures shown and described herein are extremely simple in construction and application and avoid the use of any metal clips or other extraneous means for maintaining them in position thus reducing the 25 number of parts to a minimum and also reducing the labor necessary to completely construct floors and the like. The present type of closure may be constructed of any 30 suitable material such as light metal or the like and in use avoid the formation of any projections or protuberances on the upper or lower surfaces of the blocks and leave the same absolutely even. As there is no 35 force tending to separate the metal closures from the blocks, the slightest pressure of the side members is sufficient to hold the closures in position on the block over the open ends thereof.

40 50 Various changes in the specific forms shown and described may be made within the scope of the claims without departing from the spirit of my invention.

I claim:—

55 1. A floor or ceiling construction comprising a plurality of open ended blocks spaced apart to form channels adapted to receive reinforcing rods and coalescent material, closures extending transversely of said blocks 60 and beyond the peripheries of the end openings whereby the latter are completely covered and end members forming continuations of said closures at opposite ends there-

of and extending along opposite surfaces of said blocks whereby said closures are maintained in position. 65

2. A floor or ceiling construction comprising a plurality of open ended blocks spaced apart to form channels adapted to receive reinforcing rods and coalescent material, 70 closures extending transversely of said blocks and beyond the peripheries of the end openings whereby the latter are completely covered and resilient end members forming continuations of said closures at opposite 75 ends thereof and arranged to grip two opposite surfaces of said blocks whereby said closures are maintained in position.

3. A floor or ceiling construction comprising a plurality of open ended blocks spaced apart to form channels adapted to receive reinforcing rods and coalescent material, 80 projections extending lengthwise of each block in proximity to opposite edges of said blocks and having undercut surfaces whereby single dove-tail recesses are formed on opposite surfaces of each block, closures in surface engagement with the ends of said blocks and extending across the open ends thereof to close the same and end members 85 forming continuations of said closures at opposite ends thereof and fitting into said dove-tail recesses to maintain the closures in position.

4. The combination of an open ended 90 block, a closure in surface engagement with an end face of said block and closing an open end thereof and members forming continuations of said closure at opposite ends thereof and extending along opposite 100 surfaces of said block to maintain said closure in position, the distance between the free ends of said members being normally less than the distance between the opposite surfaces of the block engaged thereby. 105

5. A floor or ceiling unit comprising an open ended block, projections extending in pairs along opposite surfaces of said block in proximity to opposite edges thereof and having undercut surfaces whereby a single 110 dove-tail recess is formed on each of said opposite surfaces, a closure in surface engagement with an end face of said block and closing an open end thereof and members forming continuations of said closure at opposite 115 ends thereof and extending into said dove-tail recesses to maintain said closure in position.

In testimony whereof, I have hereunto set my hand in the presence of two subscribing 120 witnesses.

FERDINAND BURCHARTZ.
